United States Patent Office.

WILLIAM H. RANNELS, OF OAKLAND MILLS, PENNSYLVANIA.

Letters Patent No. 65,483, dated June 4, 1867.

IMPROVED HARNESS-PAD BLOCK.

The Schedule referred to in these Letters Patent and making part of the same.

TO ALL WHOM IT MAY CONCERN:

Be it known that I, WILLIAM H. RANNELS, of Oakland Mills, in the county of Juniata, and State of Pennsylvania, have invented an Improved Block for Forming Harness-Pads; and I do hereby declare the following is a full and exact description thereof, reference being had to the accompanying drawings, making part of this specification—

Figure 1 being a top view of the block.

Figure 2, a side view thereof.

Like letters designate corresponding parts in both figures.

The block A has a base, *a*, of sufficient width to contain the other parts; the form *d* being over the middle, and the crimping holders or ledges *ff* at the sides of the form. A nose projection extends forward from the front end. The bow-lever presser B has two legs, *ii*, which are respectively pivoted at their ends *hh* to oblique staples *gg*, the ends *hh* curving outward to correspond with the position of the staple hinges, substantially as shown in fig. 1. This form of hinging gives stiffness to the legs of the presser and braces them in position. It also prevents the presser from being turned up or back too far to be out of position to work with. The presser has a handle, *b*, by which it is operated, and a link, *C*, pivoted thereto, and of such length that when the presser is brought down with sufficient pressure upon the block, it can pass around the projection *c* of the block and hold the presser down, substantially as shown by black lines in fig. 2.

To use the block, the presser is raised into the position shown by red lines in fig. 2, then the leather is placed over the form *d*, and the presser brought down and locked, thus crimping the leather for the pad, and fastening it down to the crimping holders *ff* till the form is given to the leather and set permanently.

What I claim as my invention, and desire to secure by Letters Patent, is—

The bow-presser B, having its legs curved outward and hinged to oblique staples *gg*, in combination with the block A, when constructed as herein specified.

The above specification of my improved block for forming harness-pad, signed by me this seventh day of January, 1867.

WM. H. RANNELS.
